US00D515379S

(12) **United States Design Patent** (10) Patent No.: **US D515,379 S**
Corcoran (45) Date of Patent: **** Feb. 21, 2006**

(54) **CORDLESS POWER TOOL**
(75) Inventor: **Michael Corcoran**, Hexam (GB)
(73) Assignee: **Black & Decker Inc.**, Newark, DE
(US)
(**) Term: **14 Years**
(21) Appl. No.: **29/219,222**
(22) Filed: **Dec. 14, 2004**
(30) **Foreign Application Priority Data**
Jun. 29, 2004 (GB) 3017860
(51) LOC (8) Cl. **08-05**
(52) U.S. Cl. **D8/68**
(58) **Field of Classification Search** D8/14.1,
D8/61, 62, 63, 64, 65, 66, 67, 68, 69, 70;

(57) **CLAIM**

The ornamental design for a cordless power tool, as shown and described.

DESCRIPTION

FIG. 1 is a left/front perspective view of a cordless power tool showing my new design.

FIG. 2 is a left side elevational view thereof.

FIG. 3 is a right side view thereof.

FIG. 4 is a front view thereof.

FIG. 5 is a rear view thereof; and,

FIG. 6 is a top plan view thereof.

1 Claim, 5 Drawing Sheets
